Primary Examiner — Angela J Lee(74) *Attorney, Agent, or Firm* — Daniel P. Malley; Bond Schoeneck & King, PLLC**CLAIM**

The ornamental design for protective electrical wiring device, as shown and described.

DESCRIPTION

FIG. 1 is a plan view of the protective electrical wiring device in accordance with a first embodiment of the design;
FIG. 2 is an isometric view thereof;
FIG. 3 is a plan view of the protective electrical wiring device in accordance with a second embodiment of the design; and,
FIG. 4 is an isometric view thereof.

The broken lines shown in the drawings represent portions of the protective electrical wiring device that form no part of the claimed design.
